DAVID J. WILCOXSON, OF MILAN, OHIO, ASSIGNOR TO HIMSELF AND A. J. MOWRY, OF SAME PLACE.

Letters Patent No. 97,013, dated November 16, 1869.

IMPROVEMENT IN THE MODE OF ATTACHING SEATS TO WAGONS.

The Schedule referred to in these Letters Patent and making part of the same.

To all whom it may concern:

Be it known that I, DAVID J. WILCOXSON, of Milan, Erie county, in the State of Ohio, have invented a new and improved Key for Securing in Place Slotted Tenons; and I hereby declare the following to be a full and exact description thereof, reference being had to the accompanying drawing, forming part of this specification.

The nature or essence of my invention consists in providing for a standard, riser, or other fixture, to be secured to its bearing or support by one or more slotted tenons, sliding beneath a plate, or in a recessed mortise, a key connected to the standard by a slot and pin.

The arrangement and operation of the device will be fully set forth below.

In the drawings hereinbefore mentioned—

Figure 1 is an elevation of a spring-riser or standard with its bearer and key.

Figure 2 is a plan of the bearer, showing the mortises through the plate, and, by dotted lines, the recesses beneath the top plate.

The standard or riser A, supporting the spring G, is provided with the slotted tenons a, b, and c, and the bar or bearer B, with the mortises a', b', and c', extending on one side under the plate D, (as shown in dotted lines on fig. 1,) so as to receive the projecting portion of the tenons below the slot e.

To one of these tenons, as a, I apply the key F, secured to the riser above the tenon, by means of the pin h, passing through the projecting shoulders i of the key, and through the slot k, in the riser A.

When the riser or standard is lowered, for the ten-

ons to enter the mortises, the key F is stopped by the plate D, the pin h sliding up in the slot k, and the key takes the position shown by dotted lines on fig. 1.

The riser A is then pushed forward until the plate D enters and fills the slots e, when the key F is slipped down through the plate D, behind the tenon a, to its former position, relatively to the standard A, and thus secures all the tenons in their places, and, consequently, the standard is firmly secured upon the bearer B.

To release it, the key F is slipped up again out of the mortise, and the standard may then be drawn back, and the tenons lifted out of their respective mortises.

By this simple construction and arrangement, I provide an efficient key, which remains connected to the standard, but which, whatever its position may chance to be, offers no obstruction to the entrance of the tenon, and only requires to be slipped down to its place, when the standard has been properly adjusted.

The foregoing being a description of my improved slotted tenon-key,

What I claim, and desire to secure by Letters Patent, is as follows:

In combination with the slotted tenon a, the key F, for securing it in place, when said key is held by a pin, h, sliding in a slot, k, substantially as herein set forth.

DAVID J. WILCOXSON.
